US0D1012869S

(12) **United States Design Patent** (10) **Patent No.:** **US D1,012,869 S**
(45) **Date of Patent:** **** Jan. 30, 2024**

(54) **CONTROLLER**

(71) Applicant: **Shen Zhen Shi Mei Er jia Ke Ji You Xian Gong Si**, Shenzhen (CN)

(72) Inventor: **Weixin Zhao**, Shantou (CN)

(**) Term: **15 Years**

(21) Appl. No.: **29/819,566**

(22) Filed: **Dec. 16, 2021**

(51) **LOC (14) Cl.** **14-03**

(52) **U.S. Cl.**

USPC **D13/168**

CLAIM

The ornamental design for controller, substantially as shown and described.

DESCRIPTION

FIG. 1 is a top perspective view of controller, showing my new design;

FIG. 2 is a bottom perspective view thereof;

FIG. 3 is a top plan view thereof;

FIG. 4 is a bottom plan view thereof;

FIG. 5 is a left side elevational view thereof;

FIG. 6 is a right side elevational view thereof;

FIG. 7 is a front elevational view thereof;

FIG. 8 is a rear elevation view thereof;

FIG. 9 is a partial enlarged view of FIG. 1;

FIG. 10 is a partial enlarged view of FIG. 1;

FIG. 11 is a partial enlarged view of FIG. 1; and,

FIG. 12 is a partial enlarged view of FIG. 1.

The broken lines showing portions of the clip in FIGS. 2 and 5-7 views are for illustrative purposes only and forms no part of the claimed design.

1 Claim, 12 Drawing Sheets
